UNITED STATES PATENT OFFICE.

JOHN CHAPMAN, OF NEWINGTON, CONNECTICUT.

KNITTING-MACHINE.

SPECIFICATION forming part of Letters Patent No. 290,972, dated December 25, 1883.

Application filed November 12, 1881. (No model.)

To all whom it may concern:

Be it known that I, JOHN CHAPMAN, of Newington, in the county of Hartford, and State of Connecticut, have invented certain new and useful Improvements in Knitting-Machines, of which the following is a specification.

My invention relates to improvements in knitting-machines, in which I employ a peculiar sinker or slide having a side projection or projections for closing the spring-bearded needles, and other features hereinafter described, and in which machine said sinkers or slides are combined with mechanism for giving them certain motions; and the objects of my improvements are to enable the machine to knit stripes, plaids, and various figures or patterns, and to make a sinker which will do the pressing, landing, dividing, and knocking over. I attain these objects by the mechanism illustrated in the accompanying drawings, in which—

Figure 1 is a sectional view of a machine having my improved sinkers and adapted for knitting fancy patterns. Figs. 2, 3, 4, and 5 are side elevations of another style of sinker, which is adapted for use in connection with a part of my improvements. Figs. 6, 7, 8, and 9 are side elevations of other styles, and adapted for use upon different styles of machines. Fig. 11 shows a side elevation of the stationary sinker-cam for a circular frame, together with an edge view of two of sinkers resting thereon. Fig. 12 shows an edge view of said cam and a side view of said sinkers. Fig. 13 is a plan view of detached parts, showing more fully the means for moving the sinkers. Fig. 14 is a partial edge view and section of the cam-ring on line x x of Fig. 13. Fig. 15 is a side view of the cam for raising the inner end of the sinkers. Fig. 16 is a partial elevation and section on the line 2, Figs. 13 and 14. Fig. 17 is a like view on the line 3, Figs. 13 and 14. Fig. 18 is a detached view of the mechanism for moving the jacks 'E, Fig. 1; and Fig. 19 is a vertical section, partly in elevation, of the main portions of my machine, the same being taken on a plane running transversely through my machine from front to rear.

My sinkers are adapted for use upon several

different kinds of machines, as will be inferred from the various styles of sinkers herein illustrated, but in all of them there is the narrow neck or beam b and the pin or side projections upon one or both sides. In most of them there is the dividing-nib c , the outer end of which points toward the forward end of the sinker, and the upper edge of which is substantially parallel to the length of the straight neck or beam, so that it may pass under the thread when in the position represented in Fig. 3, and so that the thread will not be liable to slip off the nib when the sinker rises and divides the stitch, as shown in Fig. 4. The upper and lower edges of said beam are not only straight but they are substantially parallel to each other, so that the work may ride properly back and forth on said neck as the latter moves endwise from the position represented in Fig. 4 to that represented in Fig. 5.

Inasmuch as various cams or other mechanism may readily be arranged to impart certain motions to other parts when the motions are once described, I do not wish to confine myself to the particular mechanism herein illustrated for so doing, but reserve to myself the right to select such cams or known mechanism as may be best suited to the purpose of imparting the motions herein described to my sinkers.

That part of my invention which is referred to in the first claim is applicable to all of the forms of sinkers herein shown and described.

For convenience, I will first describe the operation of the sinkers represented by Figs. 2 to 5, inclusive, Sheet 2, and then describe the mechanism for so operating them. This particular form of sinker is designed for use with stationary needles arranged either in a straight or circular frame. It may also be used in connection with sliding needles, if desired. When used with stationary needles, the first movement of the sinker or slide is to pass longitudinally and horizontally between two needles properly supplied with yarn, so as to press or sink the yarn between the spring-bearded needles d and under the beards, as shown in Fig. 3. While the slide or sinker is thus advanced, the front end of the slide is raised vertically by any suitable mechanism

into the position represented in Fig. 4. In moving into this position, the pin *a* (which in this particular slide projects a short distance from each side of the sinker or slide) comes in contact with the spring-beards of the two adjacent needles and presses the spring-beards toward the body of the needles and holds them so pressed as the slide rises. In case there were only one side projection or pin, *a*, on the slide, then the beard of only one needle would be pressed. The neck or beam *b* lifts the work and lands the loop at the same time that the beards are pressed and the nib or nose *c* elevates and divides the stitch, as shown in Fig. 15 4. Thus it will be seen that the pressing, landing, and dividing is all done by one motion—to wit., an upward vertical movement of the forward end of the slide or sinker. The sinker, while it is still elevated, is next moved 20 backward into the position represented in Fig. 5, when the knocking-over or inclined cam *A* on the end of the slide comes in contact with the work to knock it over, as shown in Fig. 5. The slide is then depressed into the level represented in Fig. 3; but farther back the thread is again laid in proper position in front of the needles, and the operation is repeated as before. In Figs. 1, 3, 4, and 5, *e* designates the thread, *f* the thread-guide, 30 and *g* the fabric.

I have herein used the term "stationary needles" in contradistinction to longitudinally-reciprocating needles. It is, however, immaterial whether the needles and sinkers revolve by a stationary cam-ring or other mechanism for imparting the longitudinally-reciprocating movement to the sinkers, or whether the latter revolves while the former are stationary.

40 In Figs. 11, 12, 13, 14, 15, 16, and 17 I have shown means for imparting the hereinbefore-described movements to said sinkers, in connection with a circular frame, and in which the cams are stationary, while the sley, needle-cylinder, comb, and sinkers revolve. These sinkers, as hereinbefore described, move individually as they are in succession acted upon by or act against suitable inclines or cams. *H* designates the outer part of the stationary 45 ring. *I* is a rotating comb-frame for carrying the sinkers; *J*, the needle-cylinder with the needles *d* mounted thereon. The position for the sley is indicated by the broken lines at *J'*. Just inside of the needle-cylinder is a stationary cylinder, *K*, upon the upper end of which there is a cam, *o*. Over the comb-guide there is the stationary cam-ring *L*, having inclines *p p'*, Fig. 13, upon its edge, and inclines *q q'*, Fig. 14, upon its under side. The cam *G'* is 55 bolted to the ring *H*, so as to project its end over the comb-frame and sinkers at a point between the inclines *p p'* of the cam-ring *L*. The parts *H* and *L* are connected together by any suitable means—as, for instance, by straps 60 or bridges bolted to the upper side of said parts—which, when taken together, form prac-

tically a single stationary cam-ring. The parts are mounted as follows: Upon a frame, cross-bar, or table of a suitable stand a stationary shaft is affixed, projecting upward. Surrounding this shaft is a hollow shaft or sleeve carrying a suitable driving-gear, and also all of the revolving parts—that is, the sley, the needle-cylinder and the comb-frame—so that said parts revolve with the sleeve and are supported by it, while the shaft about which said sleeve and connected parts revolve is stationary. Suitable arms or a hub at the bottom of the cam-cylinder *K* connect said cylinder to the upper end of the stationary shaft and support said cylinder stationary at the proper height 80 relatively to the needle-cylinder. The ring *H* is connected to the stand or frame by vertical posts at points outside of the comb-guide. These revolving parts are driven and stationary parts supported in the same way as the revolving needle-cylinder. The central stationary shaft and the stationary parts both outside and inside of the needle-cylinder, are driven and supported as in the old and well-known round 90 English frame, to which reference is made.

In Fig. 13 I have shown only two sinkers; but in practice the sinkers will be placed one for every needle throughout the whole circle of needles. As each沉器 in the comb-frame presents itself to the cam *G'*, the wing *m* rides up its incline over the end of said cam to throw the沉器 endwise inward into the position represented for the沉器 in Fig. 3, and the left-hand沉器 in Fig. 13. The under surface of the cam-ring *L* is flat at the portion which is at the right of the broken line 1, Figs. 13 and 14, and the沉ers consequently are held down flat while they are moved inward by the cam *G'*. So soon as each沉器 reaches 105 the corner of the cam *G'* which coincides with the line 1, the inner end of the沉器 begins to be forced upward edgewise by riding up over the cam *o*, and it reaches the summit of said cam when it reaches the next corner of the cam *G'*, and is under that point in the ring *L* designated by the line 2, and the under surface of the cam-ring is made to slant upward from the line 1 to line 2, or is otherwise cut away so as to allow the cam *o* to thus elevate 110 the沉ers. Figs. 4 to 16 illustrate the position of the沉器 just as it reaches said point. The under face of the ring *L* at this point should be cut away sufficiently, as represented in Fig. 16, to allow the沉器 to draw back 115 freely, as hereinafter described. The cam *o* holds the inner end of the沉器 thus elevated while it is passing from the line 2 to 3, during which time the incline *p* on the cam-ring *L* acts upon the wing *m* of the沉器 to draw it 120 backward into the position in which it is represented in Figs. 5 and 17. As it passes onward from the line 3 to 4, it rides off the last incline of the cam *o*, and the under face of the cam-ring *L* from 3 to 4 is inclined downward, 125 as shown in Fig. 14, so as to force the沉器 downward again into its horizontal position 130

within the comb-frame L. From the line 4 onto the left the under face of the cam-ring L is flat to hold the sinker down until it reaches another set of cams in its circuit. I have here-
5 in shown but one set of cams for moving the sinkers, but there may be as many sets of cams on the respective rings and cylinders as may be desired, and as many threads may be fed into the machine as there are sets of cams.
10 The machine, however, will knit correctly with only one set of cams, in which case the entire under surface of the cam-ring will be flat, except that between the lines 1 and 4, as shown in Fig. 14. There can be one set of
15 cams for every two inches in the circle of needles, and they may be made to work with one set for every one and a half inch; but I prefer to leave two blank spaces without any cams for five or six inches at the front and
20 rear of the machine for convenience of repairs and for running on the fabric.

If desired, by the employment of a sinker with the cam *n* on its under side, which will engage the top of cam *o* and elevate the sinker
25 during its backward movement to knock over the work, the cam *o* need not be made so high, and the rise of its incline would not be so steep. As said before, these sinkers move individually, and they also have an individual action,
30 so much so that one sinker and two needles alone will knit. By having the cam *o* and needles arranged a little lower, or having the comb-frame and cam-ring L arranged relatively higher, the machine may be constructed
35 so as to work without giving the sinker so great an extent of vertical movement as is represented for them in Figs. 3, 4, 5, 16, and 17.

In Fig. 1 the thread-guides *f* are mounted upon the thread-guide bar B, so as to move
40 vertically, said bar also moves longitudinally and carries each thread-guide from one needle to the next at the formation of each stitch, and the needles *d* are mounted in like manner upon the needle-bar C, to move vertically, all
45 substantially as in many other straight frames. This straight frame is supplied with a thread for every needle for knitting a stocking-stitch, and the threads may be of different colors.

Examples of machines with a thread-guide
50 and thread for every needle and mechanism for moving the thread-guide bar and needle-bars which is applicable to my machine may be found in patents to M. Townsend, June 29, 1880, No. 229,487, and No. 246,248, Au-
55 gust 23, 1881, to G. Upton.

Machines having a thread-guide bar and needle-bar, with mechanism for moving them in the manner hereinbefore described in my machine, are old and well known, and the
60 mechanism for moving these bars does not need to be described to one skilled in the art of knitting-machines.

The slides or sinkers D are arranged to move longitudinally in a horizontal direction, but
65 not to move vertically in the manner hereinbefore described, except by means of the cam

n striking the upper edge of a stationary bar when the sinker is drawn back. They also have the side projection, *a*, and neck or beam *b*, but the pin *a* projects only from one side. 70 These sinkers have their longitudinal movement imparted to them by means of the swinging jacks E, to which they are pivoted. A friction-spring, *h*, bears upon the upper ends of the jacks, to hold them back when not forced forward. The jacks pass through between two thin plates, F, which are moved by means of suitable cams up over the back of the jacks by degrees—that is, step by step—and when they have nearly reached the upper ends of 80 the jacks they are caused to descend in the same manner. These plates F have also a short horizontal movement imparted to them to move the jacks and carry the sinkers D longitudinally. Fig. 18 shows the mechanism 85 for imparting these movements to the plates F.

M designates a horizontally-moving block, one end of which is mounted eccentrically upon the shaft N, whereby the revolution of said shaft reciprocates said block M horizontally. 90 At the other end of said block there are vertical slots *r* *r*, within which is fitted the vertically-moving cross-bar P. Said cross-bar is connected by a pin, *s*, to the upper end of a slotted slide, Q. The lower end of said 95 slide is provided with a friction-roller, *t*, and said lower end is held in position by means of a pivoted block, *n*, secured to the frame-work of the machine, and fitting within the slot of said slide, whereby the slide may have a slight 100 rocking motion in addition to its vertical movement.

Underneath the friction-roller *t* of the slide Q there is a cam, R, mounted on shaft or stud S by the side of the ratchet-wheel T. One end 105 of a weighted or spring-actuated pawl, U, engages said ratchet, while its opposite end is eccentrically mounted upon the shaft N, whereby the ratchet-wheel is moved the space of one tooth at a time for every revolution of the 110 shaft N and every horizontal movement of the block M. The ratchet-wheel is prevented from moving backward by the spring *v* or other equivalent means. These parts are located at the end of the machine, and there is a block, 115 M, cross-bar P, slide Q, and cam R at each end of the machine. The plates F are bolted at each end to the cross-bars P, which should have a slotted connection for the fastening-bolts, so that said plates may be adjusted to and from 120 each other, to accommodate jacks of different widths. The jacks rest between the plates F F, as shown in Fig. 1. Thus it will be seen that the horizontal movement of the block carries the jacks and sinkers back and forth, 125 while the cam R lifts the plates F step by step up over the body of the jacks, until the point of said cam passes the friction-roller, and then the plates will descend in like manner.

Notches *i* *i* are cut in the back edges of the 130 jacks, to form any desired pattern. The number of jacks having said notches, and the

number of notches in the jacks, depends entirely upon the pattern to be knit. Whenever the thin actuating-plate F is directly in the rear of a notch in one or more of the jacks, 15 and the plates move forward, it will enter said notch or notches, and for that reason the sinker will not be carried forward far enough to press the spring-beard of the needles to close said beard, so that the thread which is 20 looped on the needle, ready to be thrown off, will be retained thereon until the next movement of the sinkers, when, instead of a single loop, there will be two loops to be thrown over the ends of such needles as did not have their 25 beards closed in the former movement of the sinkers, thereby throwing a thread of one color to the back or inside of the fabric, and bringing a thread of a different color to the front or face side of the fabric. Thus it will be 30 seen that the notches in the backs of the jacks produce the figure in the fabric. For instance, if the notches in the back of the jacks are so placed with reference to each other that when viewed from the rear they form a dia- 35 mond-shaped figure, then a diamond-shaped figure will be produced in the fabric. More elaborate figures may be formed in the same manner.

Vertical stripes, plaids, and diamonds may 30 be knit without the aid of the jacks by notching the end of a part of the sinkers, as shown at k, Figs. 5 and 6, and having the sinkers forced endwise by a narrow cam, so that when a notched sinker comes in front of the 35 cam it will not be forced forward far enough to close the spring-beard upon the needle at the time when the sinkers are lifted. Figs. 11 and 12 illustrate such a cam, G, with two sinkers, one of which is notched and the other 40 not. These cams and sinkers are adapted for use with the round frame hereinbefore described. If at any time it is desired to knit plain work it may be done by means of the same sinkers by moving the adjustable piece 45 l on the cam G forward and setting it with its edge flush with the edge of said cam. The sinkers will then be actuated by the cam striking upon the rear edge of the wings m, and they will all be moved the same distance 50 whether notched or not. The cam G is shown of such shape that the notched sinkers are at first forced inward the same distance as the rest; but so soon as they pass the corner of the incline they may fall backward a little, as 55 shown by the left-hand sinker in Fig. 11. The sinkers are not, however, raised to press the beards of the needles until after they pass the point of the incline which throws them inward, so all the notched sinkers fall back, as 60 shown, and fail to close the beards, as before specified. This non-motion or falling back so as not to close the beards produces a strip which is commonly called a "tuck-stitch," and is quite common in the backs of gloves, 65 but produced by different mechanism. When this tuck-stitch is made with threads of differ-

ent colors, it brings one color to the front and the other to the rear, thereby producing vertical stripes in colors. Whenever it is desired to end these stripes and still continue knitting, 70 the piece l may be set flush with the edge of cam G, and the work then made will be plain. Thus by changing the cams several times while knitting a piece of fabric that piece will be formed with plain and striped sections alternately, either all of equal length or some long and some short, as may be desired. The horizontal stripes are formed by running different colored threads into the machine, and my arrangement of the sinkers enables many threads 80 to be used. For instance, forty threads of any desired colors may be knit into the fabric for every revolution of the machine, which threads may be divided into a great variety of horizontal stripes either wide or narrow, or both, 85 which in connection with the arrangement for knitting vertical stripes will produce plaids in great variety.

In Fig. 6 I have shown a sinker which I intend to use upon a semicircular frame for making fashioned work. In this sinker I make the side projection, a, in the form of a friction-roller.

In Fig. 7 I have shown another style of sinker for use upon a round frame.

In Fig. 8 I have shown a sinker similar to that shown in Fig. 1 which I design for use upon a flat frame. This sinker differs from that shown in Fig. 1 only by the addition of the inclined cam A.

In Fig. 9 is another sinker for a flat frame in which the side projection is cam-shaped, and this projection may, if desired, be made adjustable to and from the needles.

In Figs. 1, 6, 7, 8, and 9 the cam n on the under side of the sinker strikes a stationary bar or beam at the last end of its backward movement and throws up the sinker for knocking over the work, producing substantially the same result as if the cam were upon the upper edge of the sinker, as in Figs. 2 to 5, inclusive. In some cases it is desirable to divide the knocking-over cam upon both sides of the sinker, as shown at A n in Figs. 6, 8, and 9.

I am aware that an English patent shows a series of sinkers of a somewhat similar form to mine having side projections for closing the beards of the needles, which sinkers are mounted on a bar to move all together and incapable of individual movement, and I hereby disclaim the same.

I claim as my invention—

1. The combination of spring-bearded needles, the sinkers having side projection, and mechanism for pressing the projections on part of said sinkers against the needle-beards to close them while the remainder of the sinkers are not so pressed, substantially as described, and for the purpose specified.

2. The combination of spring-bearded needles, the sinkers having side projection, the

jacks E, having pattern-notches in their backs, and mechanism acting upon the back of said jacks to throw the sinkers forward, substantially as described, and for the purpose specified.

5

3. The sinker having the side projection, the neck or beam, and the cam *n* upon the

under side at the outer end of said beam, substantially as described, and for the purpose specified.

JOHN CHAPMAN.
